RAPPER MECHANISM

Herman C. Engelman, Staten Island, N. Y., assignor to Research Corporation, New York, N. Y., a corporation of New York

Application January 4, 1943, Serial No. 471,271

9 Claims. (Cl. 259—1)

The present invention relates to means for rapping or vibrating apparatus utilized in removing suspended particles from gases and its general purpose is to free the surfaces of such apparatus of collected particulate material. The invention relates more specifically to a mechanical system and apparatus which will subject the electrodes of an electrical precipitator to the resilient jarring provided by the impact of a freely falling ball.

The electrodes of electrical precipitators used in most installations involving the removal of suspended dusts and the like from gases must be shaken or jarred from time to time to remove the material which has been electrically or mechanically deposited on the surfaces of the electrodes if the deposits are not to build up and interfere with the normal operation of the precipitator. Various devices have been proposed for shaking precipitator electrodes, many of them comprising mechanically operated hammers. Hammers have not been altogether satisfactory. If the head is fastened to the operating mechanism with a strong, stiff handle, the handle restrains the movement of the head at the instant of impact and prevents resilient reaction between the head and the structure being hit. This resiliency, or ability to rebound and vibrate, is a very important factor in setting up movements throughout the electrode structure and loosening deposits on different portions of the electrode surface. Hammers with flexible handles produce more effective vibration with a blow of equal magnitude than do hammers with stiff handles but limber handles vibrate and often break of fatigue after rather short periods of operation.

The present invention provides means for moving a ball, say of fracture resisting iron alloy, back and forth along a path above the electrode structure to be rapped and causing the ball to fall—under the force of gravity (which may be augmented by mechanical forces), at designated locations along the path, upon anvils attached to the structure. The electrode structure may be a single more or less rigid electrode comprising discharge and/or collecting surfaces, or a single structural member giving support or guidance to one or more electrodes, or a frame made up of structural members from which depend a considerable number of electrodes. The invention will be described and illustrated with reference to an electrode structure comprising a built-up frame, suspended in the top header of

an electrical precipitator in electrically insulated relation to the precipitator housing, and vertically extending discharge electrodes suspended from the frame.

5 The principal object of the invention is to provide means for subjecting an electrode structure of an electric precipitator to the impact of a missile of substantial mass, such as a metal ball, which is substantially unrestrained, mechanically, at the time of impact, for the purpose of jarring deposited material from the surfaces of the electrodes.

10 A further object of the invention is to provide a pair of anvils on an electrode structure and means for repeatedly raising a rapping ball and causing it to drop alternately on first one and then the other of said anvils, the means provided being characterized by freedom from friction and wear and being capable of continuous and effective operation with non-varying results for long periods of time.

15 Another object is to provide means for dropping a rapping ball on an electrode structure, the means being so constructed that balls of different size or weight can be readily substituted one for another without stopping the operating mechanism and being capable of changes in operating frequency without making any change except one in prime mover speed.

20 Another object is to provide a ball elevating mechanism which imparts an accelerating mechanical push to the ball as it leaves the elevating mechanism and begins its downward course pulled by the force of gravity.

25 Still another object is the provision of a dual purpose structure made up of a frame for supporting the electrode elements and a frame for supporting the rapping mechanism, characterized by resilient spring means between the two frames of the structure, thus preventing rapping jars imparted to the electrode support from being transmitted with any severity to the mechanism support.

30 Other objects and purposes of the invention will be set forth in the following description wherein reference will be had to the accompanying drawings, in which:

35 Fig. 1 is a side elevation of apparatus illustrating a simple embodiment of the invention;

40 Fig. 2 is a partial side elevational view of apparatus illustrating a preferred embodiment of the invention;

Fig. 2a is a detail sectional view on line 2a—2a of Fig. 2;

Fig. 2b is a plan view of a detail comprised in the apparatus shown in Fig. 2;

Fig. 3 is a plan view of the electrode structure which supports the electrodes and operating mechanism shown in Fig. 2;

Fig. 4 is a diagrammatic view, in side elevation, of the ball raising cradle illustrated in Fig. 2, and

Fig. 5 is a fragmentary side elevational view of a different embodiment of the invention.

In the apparatus illustrated in Fig. 1, horizontally positioned structural members 1 and 2, which are here shown as parallel channels, support angle members 3 and 4 which are illustrative of the members from which discharge electrodes 5 with weights at the bottom 6 are suspended. Channels 1 and 2 also support, on cross plates 7, anvils 8 and they support bearing block 9 which in turn supports horizontally extending shaft 10 on which ball raising cradle 11 is mounted and with which it oscillates. Cradle 11 is made up of a hub 12 to which are fastened arms 14 and 14' which are shown as made up of a continuous piece of flat metal riveted to hub 12. Near the end of arms 14 and 14' are fastened shelf members 15 and 15', respectively, upon which the ball 24 rides as it is elevated as will be more particularly described later. Ends 16 and 16' of arms 14 and 14', respectively, are sufficiently narrow adjacent track rods 20 and 21 to permit movement of the arms between the rods but the ends of the arms beyond the rods spread out and are forked to straddle anvils 8 and to provide a seat for the ball while it is being lifted. Ball 24 is shown as it is about to hit the anvil at the left of the figure. Beams 1 and 2 are supported by vertical rods 26 (one rod only being shown) which pass through insulating bushings 27 which cover openings in plate 28. Bushings 27 are in a compartment which houses such insulators as are necessary to mechanically support rods 26 and the structure supported thereby and to electrically insulate the rods and electrode structure from the grounded portions of the precipitator.

A rod 30 attached at its upper end to a crank (not shown) is connected at its lower end through spring assembly 40 to hollow rod 31, rotatively connected to crank 32 which is rigidly attached to shaft 10. In spring assembly 40, a plate 33 is fastened to rod 30, the end of the rod is drilled or otherwise fabricated to receive a plurality of guide pins 38 (only one of which is shown) and the rod is dimensioned to fit into hollow rod 31 with a sliding fit. A plurality of slots 39 machined in hollow rod or tube 31 match the holes in rod 30 for pins 38, with which the slots make a sliding fit, a stop plate or washer 37 fits over rod 31 with a sliding fit, and a collar 35 is fitted to the end of rod 31 by screw threads or other suitable means. During assembly as the end of rod 30 is inserted into the hollow end of rod 31 a helical spring 34 is placed over rod 30 between collar 35 and stop plate 33, and another helical spring 36 is placed over hollow rod 31 between washer 37 and collar 35. With collar 35 fastened on the end of rod 31 and pins 38 inserted in the end of rod 30 behind washer 37, springs 34 and 36 are under appreciable, and approximately equal compression, the dimensions required to produce such conditions being easily ascertained by computation or by trial.

The manner of operation of the ball moving apparatus shown in Fig. 1 will be described while referring to the figure. Cradle 11 comprising arms 14 and 14' is oscillated on shaft 10 by a reciprocative movement of rod 30. Cradle 11, as shown, has just come to a stop with arm 14 at the left of the vertical position after having delivered ball 24 to the top of the path provided by track rods 20, 21. Ball 24 is shown 10 about to strike anvil 8. It has been rolling down on track rods 20, 21 under the influence of gravity until it has acquired sufficient velocity to cause it to leave the guide and drop freely along a new path toward anvil 8. Just above the anvil the ball enters a cage of rods 20, 21, 22 and 23 as shown more clearly on the right of the figure. The ball will bounce and strike the anvil several times unless the cradle in the meanwhile starts to move and the forked end 16' of arm 14' raises above anvil 8, catches the ball, and begins its travel to the top of the ball path. While being raised, ball 24 cannot roll or slide upon rods 20, 21 because of shelf 15' or 15. Only after it passes the vertical position and begins to move under the force of gravity does it roll off shelf 15', or 15, as the case may be, and begin its accelerated travel down the path provided by rods 20, 21. It is lifted with, and pushed by, an arm of the cradle through an arc of somewhat more than 90° (for instance, from about 96 to 110°) in order that the component of the force of gravity which is tangent to the position on the ball path then occupied by the ball is sufficiently great to cause it to roll free of the cradle arm. A ball moving arm must not start the ball too soon, however, else the ball will reach the anvil before the other arm has moved out of the way below the anvil.

Figs. 2 and 3 illustrate apparatus which comprises improvements not found in the apparatus shown in Fig. 1, improvements found valuable in installations subjected to long continued service and in large precipitators where the electrode structures are so large that propagation of effective vibrations throughout the structures is difficult to obtain. It is to be understood in the following description of the structures which support the electrodes and rapping mechanism that the structures are symmetrical about center lines and hence only one quadrant is illustrated in Figs. 2 and 3. The electrodes to be shaken, indicated as discharge electrodes 50, say, small twisted rods, depend from horizontally extending structural angles 51 which are attached near their outer ends to structural members 52 (only one of which is shown). An anvil beam 53 is supported by angles 51 to which it is rigidly attached and on each end of beam 53 is an anvil 54. This electrode structure, made up of electrodes 50, and structural members 51, 52 and 53, the latter member comprising the anvils, depends by rods 55 (one of four being shown) from two beams 58 each made up of two structural members 59 and tie plates 61, 62, the lower ends of rods 55 being fastened to members 52 and the upper ends to plates 62. Beams 58 support a single transversely positioned beam 63 made up of two parallel members 64, here shown as structural channels, fastened in spaced apart position by plates 65 and other members as may be needed. Beam 63 serves as a rapping mounting bridge and to it are attached two plates 66 which support bearings for shaft 67 to which ball raising cradle 70 is attached and with which it oscillates. It will be noted that in this embodiment of the invention

that portion of the apparatus which supports the ball dropping mechanism is relatively independent of the electrode structure being rapped and vibrated. The separation is made more nearly complete when spring means are incorporated in the suspensions which comprise rods 55. As the spring suspension is not a part of the present invention no detailed description of the same will be given. The rapper supporting structure comprising members 58 and 63 depends by members, indicated by the rod 60, from any suitable insulated means, usually in a separate compartment (not shown) above the compartment housing the rapper support.

The ball raising cradle 70 is made up of a yoke 71, which is keyed to shaft 67, arms 72 and 73, which are attached rigidly to yoke 71, and auxiliary arms 74 and 75, which are attached, respectively, to arms 72 and 73 through pivots 76, and which comprise ball supporting shelves 77, and weights 78. Stirrups 79 attached to the ends of arms 72 and 73 pass around auxiliary arms 74 and 75 and limit the extreme outward positions which can be taken by arms 74 and 75, respectively. Also keyed to shaft 67 is a crank 82. A connecting rod 83 connects crank 82 to a shorter crank 84 and when the latter rotates about its driving shaft 85, crank 82 oscillates through an arc of about 100 degrees.

Ball 90 which is shown resting on anvil 54, may vary in its composition, size and weight; in the present example, it is $4\frac{1}{2}$ inches in diameter, is made of manganese steel, and weighs approximately 13 pounds. While moving just above the anvil, ball 90 is guided, to the extent guidance is necessary, by two bent plates 91, and a bar 92 which are held spacially positioned about the ball, as indicated in Fig. 2b, by a small frame made up of angles 93 and cross bar 94, the frame in turn being bolted to members 64 in adjustable manner.

The path taken by the ball in moving from one anvil to the other (one half only of the path is shown in Fig. 2) is provided by track rods 96, guide rods 97, and guide rail 98. The rods and rail are mutually supported near the upper end of rail 98 by partial hoop 99 which nearly encircles the group and is attached to each member by welding. An inverted U-shaped brace 100 is attached at the open end to members 64; the closed end goes over the rods and rail and is attached to these members. Plate 65, fastened across members 64, is cut out for entrance of ball 90 and is attached by welding to rods 96 and 97, and rail 98 and so positions and anchors these members.

The apparatus operates as follows: In Fig. 2, cradle 70 is shown at the extreme position reached after turning counter-clockwise. Ball 90 is at rest on the top of anvil 54. The pronged end of auxiliary arm 75 is straddling elevated top 54' of anvil 54 and is resting on the base portion of the anvil. Crank 84, after passing dead center, will turn the cradle clockwise, arm 73 will rise under arm 75 which will then rise and lift ball 90. The ball 90 will ride on the prongs of arm 75 and shelf 77 and be carried to the top of the path. As it goes over the vertical position, weight 78 will pull auxiliary arm 75 forward with accelerated velocity and throw the ball off shelf 77 and start it rolling down rods 96 of the right-hand side (not shown) of the track where at the bottom it will strike the anvil at that end of member 53. Crank 84 will at approximately the same time pass through its

other dead center position and arm 74 of the cradle will then pick up the ball and carry it counter-clockwise to the top of the path. From experience with this rapper, satisfactory removal of dust can be obtained if the ball hits an anvil about once every minute. If there is reason to speed up the apparatus to where centrifugal forces become factors in its operation, counter-balancing of the cradle and operating mechanism must receive consideration, as those familiar with the design and operation of such mechanisms will appreciate. At higher speeds the throw of booster arms 74 and 75 can be lessened; and, as ball 90 will tend to move tangentially away from rods 96 near the bottom ends of the path, the positioning of the guide assembly comprising members 91 and 92 may have to be altered.

The action of auxiliary arms 74 and 75 can best be explained by referring to Fig. 4. Ball 90 moves along an arc *m* with center *O*. Any force moving the ball must have a component which is tangent to that point of the arc where the ball is at the moment. The movement of assembly 80 made up of weight 78, shelf 77 and arm 74 can be assumed to be, for dynamical purposes, along an arc *n* passing through its center of mass and which has *o* as a center; and the magnitude of any force which tends to rotate the assembly is measured by the magnitude of the component which acts tangentially along arc *n* through the center of mass. (In a complete analysis of the problem, the movement of the assembly 80 about center *O* cannot be neglected but this factor is of minor importance in the independent movement of the assembly about center *o*). The movement of arm 72 while ball 90 is moving through a position directly over center *O* is very slow because crank 84 is then approaching dead center, and the ball receives no positive push from arm 72 to start it down the path toward the anvil. The ball must be moved into a position where the force of gravity has a tangential component of sufficient magnitude to overcome friction and start the ball on its general downward path. Now the tangential force on the ball is $g \sin A$, where g is the gravitational force and A is the angle between two lines passing through the center of the ball—one a vertical line and the other a line passing through center *O*. This angle increases in magnitude very slowly while the ball is near the vertical position. The pull of gravity tending to move assembly 80 along arc *n* equals $g \sin a$, where a is the angle between the two lines passing through the mass center of the assembly—one vertical, the other passing through center *o*. Now as arm 72 moves past the vertical position, angle a increases much faster than does angle A and the force tending to rotate assembly 80, comprised of weight 78 and associated members and having an aggregate mass preferably as great or greater than the mass of ball 90, quickly becomes great enough to pull arm 74 forward and to cause it to impart a push of considerable magnitude to the ball. It can readily be seen that the further forward the center of mass of assembly 80 is positioned with respect to center *o* the more quickly, with relation to the position of arm 72, will the force of gravity pull the assembly forward and cause arm 74 to accelerate the movement of ball 90. The position of the center of mass of assembly 80 can be varied by fastening weight 78 with an adjustable mounting and through the use of this variable mounting the time of starting ball 90

rolling down tracks 96 can be chosen to synchronize with the position of arm 75.

It is advisable to the extent practical to lower arm 75 (and, alternately, arm 74) gently, without jar or noise, to anvil 54 and to pick up ball 90 slowly and without jerking the lifting mechanism. This is possible by having the actuating crank 84 pass through "dead center" during this part of the operation. But it presents the drawback of compelling ball 90 to roll off shelf 77 at the top of the path while cradle 70 is moving very slowly. This drawback would be very real if arms 72 and 73 extended as stiff members out to the ball, but hinged and weighted booster arms 74 and 75, which move relatively independent of the speed of the cradle as they pass through the vertical position, alternately give the ball an effective push when it is most needed.

A further advantage of the construction illustrated in Figs. 2 and 3 lies in the ease with which balls can be removed. At the top of the path comprising tracks 96, there is no cover strap 98. Here the ball can be removed with the hands if the apparatus is stopped and temperature and atmospheric conditions inside the precipitator are favorable. But as it is often important to maintain operation without stopping the flow of gas, arrangements can be provided for inserting tongs or a rake through an opening, normally closed, in the side of the top header of the precipitator and picking the ball off the track and substituting a new ball or one of different size as conditions may indicate. The high voltage structure is de-energized before inserting the tongs. A lateral track, permanently installed, or inserted under a rake, can be used to run the ball toward the opening in the wall after it has been raked off of the path with the rake. This track must either be insulated or else terminated at proper distance from the precipitator wall if it is to remain in the precipitator while the latter is energized.

Fig. 5 illustrates an embodiment of the invention which permits the ball to drop freely from a considerable height without adding to the height of the apparatus. One side of the apparatus is shown; the other side is similar. Ball 104 is caused to drop on anvil 105, with restricted impact portion 105', which is mounted on a member similar to beam 53 in Figs. 2 and 3. The ball is alternately raised by booster arms 106 and 107, which are comprised in a cradle that may be mounted on a bridge, here indicated by member 122 and which is similar to cradle 70 in Figs. 2 and 3, along two parallel rods 110 comprising a track. No shelves are shown on arms 106 and 107 for carrying the ball. While useful in minimizing wear of ball and tracks, such shelves are not necessary, at least where the apparatus is used infrequently. In descending, the ball rolls on track rods 112, which are inclined but slightly from the horizontal and guide the ball to the vertical path defined by guide rods 116 and 118. Tracks 112 at position 114, which is just over the vertical path, are spread apart to let the ball drop through and go vertically downwards. Track rods 112 are comprised in a frame held together with cross rod 121 and pivoted for rotary motion about horizontal bar 120. This arrangement permits ball 104 when being moved upwardly along track rods 110 to raise the free ends of rods 112 to the by-pass position indicated by dash lines 115. After the ball passes, the free ends of rods 112 drop back upon rods 110 and provide a path along which the ball travels

downwards when again raised from the opposite side of the apparatus.

I claim:

1. Apparatus for rapping a material-collecting member comprising an anvil member mounted in vibration-transmitting relation with said material-collecting member, means providing a trackway for guiding a falling missile upon said anvil, and means movable with respect to said anvil for periodically lifting a missile from said anvil to the upper portion of said trackway.
2. Apparatus for rapping a material-collecting structure comprising a pair of spaced anvils mounted on said structure, means providing a trackway for a missile between said anvils passing through a point of maximum elevation above and substantially midway of said anvils and positioned to guide a missile at each end of said trackway into substantially vertical impact upon the corresponding anvil, and means movable with respect to said anvil for periodically transporting a missile along said trackway from a position of rest upon an anvil to a position beyond said point of maximum elevation with respect to such anvil.
3. Apparatus for rapping a material-collecting structure comprising a pair of spaced anvils mounted on said structure, an arcuate trackway positioned above said anvils to guide a missile at each end of said trackway into substantially vertical impact upon the corresponding anvil, and means movable with respect to said anvil for periodically transporting a missile along said trackway from a position of rest upon an anvil to a position beyond the point of maximum elevation of the trackway with respect to such anvil.
4. Apparatus for rapping a material-collecting structure comprising a pair of spaced anvils mounted on said structure, means providing a trackway for a missile between said anvils passing through a point of maximum elevation above and substantially midway of said anvils and positioned to guide a missile at each end of said trackway into substantially vertical impact upon the corresponding anvil, and a pivotally mounted pair of arms each having a missile-engaging portion positioned for motion along said trackway upon movement of the arms about the pivot, said missile-engaging portions being spaced along said trackway a distance slightly less than one-half the length of the trackway.
5. Apparatus for rapping a material-collecting structure comprising a pair of spaced anvils mounted on said structure, means providing a trackway for a missile between said anvils passing through a point of maximum elevation above and substantially midway of said anvils and positioned to guide a missile at each end of said trackway into substantially vertical impact upon the corresponding anvil, and a pivotally mounted pair of arms each having a missile-engaging portion positioned for motion along said trackway upon movement of the arms about the pivot, the angular relation of said arms being such that when one of the missile-engaging portions is in a position slightly beyond the point of maximum elevation of the trackway toward one of said anvils, the other of said missile-engaging portions is positioned sufficiently below the surface of such anvil to permit a missile to freely strike the anvil.
6. Apparatus for rapping a material-collecting structure comprising a pair of spaced anvils mounted on said structure, means providing a trackway for a missile between said anvils passing through a point of maximum elevation above

and substantially midway of said anvils and positioned to guide a missile at each end of said trackway into substantially vertical impact upon the corresponding anvil, a pivotally mounted pair of arms each having a missile-engaging portion positioned for motion along said trackway upon movement of the arms about the pivot, said missile-engaging portions being spaced along said trackway a distance slightly less than one-half the length of the trackway, and means for periodically swinging said arms through approximately a quadrant along said trackway.

7. Apparatus for rapping a material-collecting structure comprising a pair of spaced anvils mounted on said structure, means providing a trackway for a missile between said anvils passing through a point of maximum elevation above and substantially midway of said anvils and positioned to guide a missile at each end of said trackway into substantially vertical impact upon the corresponding anvil, and a pivotally mounted pair of arms each having a missile-engaging portion positioned for motion along said trackway upon movement of the arms about the pivot, the angular relation of said arms being such that when one of the missile-engaging portions is in a position slightly beyond the point of maximum elevation of the trackway toward one of said anvils, the other of said missile-engaging portions is positioned sufficiently below the surface of such anvil to permit a missile to freely strike the anvil, said missile-engaging portions being mounted for limited pivotal movement on said arms in the plane of movement of the arms.

8. Apparatus for rapping a material-collecting structure comprising a pair of spaced anvils mounted on said structure, means providing a

trackway for a missile between said anvils passing through a point of maximum elevation above and substantially midway of said anvils and positioned to guide a missile at each end of said trackway into substantially vertical impact upon the corresponding anvil, and a pivotally mounted pair of arms each having a missile-engaging portion positioned for motion along said trackway upon movement of the arms about the pivot, the angular relation of said arms being such that when one of the missile-engaging portions is in a position slightly beyond the point of maximum elevation of the trackway toward one of said anvils, the other of said missile-engaging portions is positioned sufficiently below the surface of such anvil to permit a missile to freely strike the anvil, said missile-engaging portions being mounted for limited pivotal movement on said arms in the plane of movement of the arms and including an adjustable weight for varying the angular movement of said missile-engaging portions.

9. Apparatus for rapping a material-collecting structure comprising a pair of spaced anvils mounted on said structure, means providing a trackway for a missile between said anvils passing through a point of maximum elevation above and substantially midway of said anvils and positioned to guide a missile at each end of said trackway into substantially vertical impact upon the corresponding anvil, means for periodically transporting a missile along said trackway from a position of rest upon an anvil to a position beyond said point of maximum elevation with respect to such anvil, and means resiliently supporting said trackway and missile-transporting means above said anvils.

HERMAN C. ENGELMAN.
